UNITED STATES PATENT OFFICE.

SHERMAN S. WITTINGTON, OF ADRIAN, MICHIGAN.

DIE FOR TYING INTERSECTING WIRES.

SPECIFICATION forming part of Letters Patent No. 747,286, dated December 15, 1903.

Application filed August 20, 1903. Serial No. 170,141. (No model.)

To all whom it may concern:

Be it known that I, SHERMAN S. WITTINGTON, a citizen of the United States, residing at Adrian, in the county of Lenawee, State 5 of Michigan, have invented certain new and useful Improvements in Dies for Tying Intersecting Wires; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 This invention relates to dies for tying or uniting intersecting wires, especially adapted for use in the making of wire fencing; and it consists in the construction and arrangement of parts hereinafter fully set forth, and pointed out particularly in the claims.

20 The object of the invention is to provide means for confining the intersecting wires of a wire fence or fabric in a manner to permit of the driving of a staple around said cross-wires to unite or tie them together, the arrangement being such as to direct the legs of the staple in forming the tie for the intersecting wires in a manner to obviate any abrupt departures from a general course in 25 a given direction and at the same time firmly unite said wires.

25 The above object is attained by the structure illustrated in the accompanying drawings, in which—

30 Figure 1 is a perspective view of the working face of one of the dies between which the cross-wires are united. Fig. 2 is a perspective view of the working face of the other of said dies. Fig. 3 is a transverse section 35 through the dies with their working faces together, showing between them the cross-wires and the tie in position thereon. Fig. 4 is a central longitudinal section through said dies as on line 4-4 of Fig. 1. Fig. 5 is a perspective view showing the cross-wires united by 40 the tie-wire, which is driven in position between the dies. Fig. 6 is a fragmentary view in perspective of the end of one of the dies looking from the opposite direction to that of 45 Fig. 2.

50 Referring to the characters of reference, 1 designates a die having the greater portion

of its face flat, but provided at one end with a raised shoulder 2. Formed in the face of the die are the parallel channels 3, which are 55 concaved or depressed near their central portion and which unite at one end in an inclined plane 4, that leads upwardly to the face of the die. The opposite ends of the channels 3 terminate in the channels 5, which are 60 formed in the vertical face of the raised portion 2 and curve inwardly or toward each other and lead into the slot 6, cut vertically through said raised portion. Crossing the parallel channels 3 is a transverse groove 7, 65 adapted to receive one of the cross-wires 8. Crossing the groove 7 at right angles is a second groove 9, which lies centrally between the channels 3 and terminates at one end in the slot 6, said groove 9 being adapted to receive the other of the cross-wires 10. The opposite die 11 is provided with an inclined way 12 for the reception of the driving-plunger, (not shown,) which is employed to force the tying-staple into position and whose 70 inner end when the dies are placed together registers with the incline 4 in the die 1. Crossing the face of die 11 is a groove 13, which registers with groove 7 in the first-mentioned die. Crossing the groove 13 at 75 right angles is a short groove 14, which is adapted to register with groove 9 in die 1. In the face of die 11 is an offset 15, adapted to receive the raised portion 2 of the opposite die when said dies are placed together, and 80 formed in the vertical face 16 of said offset (see Fig. 6) are the downwardly-curved channels 17, which are adapted to register with the channels 5 in the vertical face of the shoulder 2.

85 The tie 18, which unites the cross-strands 8 and 10, is in the form of a staple, and when the dies are placed together upon the cross-wires which lie in the registering grooves 7 and 13 and 9 and 14 and the staple or tie is forced 90 into the dies through the inclined way 12 the legs of said staple are directed by said incline and the incline 4 into the parallel channels 3 under the wire 8. A further inward movement of the staple will cause its 95 legs to enter the channels 5 in the vertical face of the shoulder 2 and the channels 17 in the vertical face 16 of the offset in the opposite die, whereby the legs of said staple 100

are curved inwardly across the wire 10 and cross each other, the terminal of one being directed from the channel 17 on one side into the channel 19 across and upon the outside 5 of the opposite leg of the staple, while the opposite channel 17 directs said opposite leg of the staple across channel 19 and into channel 20, whereby the terminals of the tie are bent downwardly upon each side of the cross- 10 wire 10, as shown at 21 in Fig. 5, completing the operation of uniting the wires 8 and 10. By forming the channels 5 in the vertical face of the shoulder 2 and the corresponding channels 17 in the vertical face of the offset 15 15 the legs of the staple may be forced across the wire 10 and caused to lie across each other, with their end portions curved inwardly, so as not to leave any sharp ends projecting from the knot, at the same time uniting the 20 cross-wires in a very substantial manner.

Having thus fully set forth my invention, what I claim as new, and desire to secure by Letters Patent, is—

1. A die for tying intersecting wires comprising opposed members, one of which is provided with a raised shoulder and with parallel channels formed in the face thereof, said member also having an inclined way with which one end of each of said parallel 25 30 channels communicates and having converging channels in the vertical face of said raised portion with which the opposite ends of the parallel channels communicate, and cross-grooves in the face of said member for the reception of the cross-wires to be tied, the 35 opposite member having an offset to receive the raised portion of the first-mentioned member, and having in the vertical face thereof,

channels which register with the channels in the vertical face of said raised portion, said 40 last-mentioned member having an inclined way and cross-grooves adapted to register with the cross-grooves in said first-mentioned member.

2. In a die for uniting intersecting wires, 45 the combination of a die member having a raised shoulder and a flat working face below the plane of said shoulder, channels for directing the tying-staple formed in the flat face of said member and extending into the vertical 50 face of said shoulder, an opposed die member having an offset in its working face adapted to receive the shoulder of the first-mentioned member, the vertical face of said offset having channels therein adapted to register with 55 the channels in the vertical face of said shoulder, each of the die members having registering cross-grooves adapted to receive the wires to be joined.

3. A die for uniting intersecting wires comprising opposed members, one of which has a raised shoulder and the other of which has an offset adapted to receive said shoulder, cross-grooves in the meeting faces of said 60 members adapted to receive the intersecting 65 wires, channels in the meeting faces of said members adapted to direct the tying-staple around said wires, said channels extending into the vertical faces of said raised portion and of said offset in opposed relation. 70

In testimony whereof I sign this specification in the presence of two witnesses.

SHERMAN S. WITTINGTON.
